UNITED STATES PATENT OFFICE

JOHN H. GOULD, JR., OF PHILADELPHIA, PENNSYLVANIA, ASSIGNOR TO
JOHN H. GOULD, OF SAME PLACE.

IMPROVEMENT IN SOFA-BEDSTEADS.

Specification forming part of Letters Patent No. 170,079, dated November 16, 1875; application filed
August 18, 1875.

To all whom it may concern:

Be it known that I, JOHN H. GOULD, Jr., of Philadelphia, Pennsylvania, have invented an Improvement in Sofa-Bedsteads, of which the following is a specification:

The object of my invention is to construct a neat, compact, and easily-adjusted sofa-bedstead, and this object I attain in the manner which I will now proceed to describe, reference being had to the accompanying drawing, in which—

Figure 1 is a perspective view of the frame of my improved sofa-bedstead; Fig. 2, a transverse vertical section, and Fig. 3 a longitudinal vertical section.

A is the front strip, B the back, D the main frame or body of the sofa, the latter having supporting legs *a* and being provided at one end with an arm, *b*, corresponding in shape with an arm formed on the front strip A, which is also provided with legs *a*. (See Fig. 1.) The frame D is provided with slots and ways for the reception and guidance of bars *d* attached one at the head and the other at the foot to the front strip A, and the arm *b* has an opening, in which slides a rod, *e*, secured to the arm of the front A. To the top of the frame D, at the front edge of the same, is hinged a supplementary frame, E, which, when a sofa is required, rests upon the top of the frame D; but when the sofa has to be converted into a bed the frame E is turned upward on its hinges, and then downward until it rests on the bars *d* and *d'* of the front A,

which has been previously extended, as shown in Fig. 1. To the bar *d* of this front portion A is hinged a frame, F, of a shape conforming to that of the arm *b* of the sofa, this frame, when turned up, as shown, resting against the rod *e* forming a continuation of said arm and serving with the latter to support the pillows, while the frame F in conjunction with the frame D, supports the bedding, both frames being slatted or otherwise arranged for the purpose. When it is desired to convert the bed into a sofa the frame E is first turned over in the direction of the arrow, Fig. 2, until it rests on the top of the frame D. The frame F is then turned down, as indicated by the arrow, Fig. 3, until it assumes a horizontal position, when it will present no obstacle to the outward adjustment of the front A to a position against the frame D.

I do not desire to claim broadly the supplementary head-frame; but

I claim as my invention—

The combination in a sofa-bedstead, of the frame D, its arm *b*, and supplementary hinged frame E, with the front A, having a hinged head-frame, F, and bars *d* *d'* adapted to ways in the frame, all as set forth.

In testimony whereof I have signed my name to this specification in the presence of two subscribing witnesses.

JOHN H. GOULD, JR.
